Specification of Letters Patent.

Patented Oct. 21, 1913.

Application filed November 14, 1912. Serial No. 731,396.

To all whom it may concern:

Be it known that I, JEAN BÉCHÉ, a subject of the King of Prussia, German Emperor, residing at Hückeswagen, in the 5 Province of the Rhine, Kingdom of Prussia, German Empire, have invented a certain new and useful File, of which the following is a specification.

This invention relates to improved files.

10 In files with cut teeth the filing surfaces are too great, whereby too great a pressure in filing becomes necessary. In order to avoid this the tooth is divided by channels or cross cuts. The channels which run parallel to the axis of the file have, however, the drawback that the file so cut forms grooves in the article filed, while files cross cut at an angle to the axis of the file occasion a sidewise slipping of the file and likewise the formation of grooves unless the strength of the workman overcomes this side slip. In order to obviate these drawbacks, the files according to the present invention are provided with two rows of 15 grooves, one sloping from right to left and the other sloping from left to right with regard to the central axis respectively. Such a construction is illustrated in Figures 1 and 2 of the accompanying drawings. By 20 this means the side slip is avoided and moreover each single file tooth is sub-divided into parts of various sizes and so there is attained the great advantage that each subdivided file tooth has a different division to 25 that preceding it. Any grooving of the work is hereby completely prevented because tooth units of different width are constantly following one another in the filing. Moreover, by this means a decidedly sharper 30 attack is secured with the file.

The accompanying drawings illustrate the invention in four figures to which reference will now be made.

Figs. 1 and 2 are diagrammatic plan views of files indicating by diagonal lines, 45 the directions of the cuts made to produce the notches. Fig. 3 is a plan view, and Fig. 4 is an edge elevation of a portion of a file.

The flat body portion A of the file has 50 primary curved teeth B, extending across the file and parallel to each other.

C indicates the narrow flat surfaces between the rows of teeth.

Each tooth B has a plurality of notches 55 D. In Fig. 1, the notches are produced by cuts along the lines E, which are spaced apart approximately the same distance as the cuts along the lines F, while in Fig. 2 the cuts along the lines E are spaced closer 60 together than the cuts along the lines F.

What I claim and desire to secure, is—

In a file having a flat body portion, primary curved teeth disposed across said body portion, said teeth having their cutting edges at the top of their vertical faces and at the inner side of their curves, said cutting edges being also transversely notched so that the notches in one primary tooth will not be in alignment longitudinally of the file with the notches in the next succeeding primary tooth and so that the inclination of a part of the notches on one side of the middle of the surface of the file will be at a different inclination from a part of those on the other side. 75

In testimony, whereof I have signed my name to this specification in the presence of two subscribing witnesses.

JEAN BÉCHÉ.
